(57) **CLAIM**

The ornamental design for a virtual reality motion controller
kit, as shown and described.

DESCRIPTION

FIG. 1 is a perspective view of a virtual reality motion
controller kit showing my new design;

FIG. 2 is a front elevational view of a foot motion controller
of the virtual reality motion controller kit, shown isolated for
clarity;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof;

FIG. 9 is a front elevational view of a waist motion controller
of the virtual reality motion controller kit, shown isolated for
clarity;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view thereof;

FIG. 16 is a front elevational view of a computer controller
of the virtual reality motion controller kit, shown isolated for
clarity;

FIG. 17 is a rear elevational view thereof;

FIG. 18 is a left side elevational view thereof;

FIG. 19 is a right side elevational view thereof;

FIG. 20 is a top plan view thereof;

FIG. 21 is a bottom plan view thereof; and,

FIG. 22 is a perspective view thereof.

The broken lines depict portions of the virtual reality motion
controller kit in which the design is embodied that form no
part of the claimed design.
